JAMES MAURICE ZWEIMAN INVENTOR

BY Edwin Leisohn

ATTORNEY

UNITED STATES PATENT OFFICE.

JAMES MAURICE ZWEIMAN, OF BROOKLYN, NEW YORK.

LOCK.

Application filed December 18, 1922. Serial No. 607,691.

To all whom it may concern:

Be it known that I, JAMES MAURICE ZWEIMAN, a citizen of Russia, having declared my intention of becoming a citizen of the United States, residing at 734 Dumont Avenue, Brooklyn, New York, have invented new and useful Improvements in Locks, of which the following is a specification.

10 This invention relates generally to improvements in locks and more specifically to permutation locks used in connection with the steering post of a motor car.

15 The principal object of my invention is to provide a locking arrangement of the permutation type applicable to the column of the steering apparatus of an automobile and having a bolt extensible into the rotatable steering shaft to prevent possible rotary movement of the latter while the bolt is engaged.

20 Further objects of the invention are to provide a locking device of this character, which is simple in construction, durable in operation, and in which by a simple operation the combination of the lock may be readily changed from one formula to another.

25 The invention consists in the novel arrangement and combination of parts more particularly described in the following specification and embodied in the claims.

30 In order to facilitate a clear understanding of the present invention, one embodiment thereof is illustratively exemplified in the accompanying drawing, wherein, Figure 1, is a plan view of my improved lock; Fig. 2 is a longitudinal sectional view taken on the line 2—2 of Fig. 1, and showing a steering post and column being embraced thereby; Fig. 3 is a detail perspective view of the bolt releasing mechanism; Fig. 4 is a perspective view of the tumblers and selectors removed from the housing; and Fig. 5 is a cross sectional view of the means for guiding the selector pin from one step in the lock to the succeeding lower step.

35 Referring to the drawings, 10 denotes a rectangular housing having laterally projecting collar 11 which is adapted to closely embrace the outer sheet 12 of a steering post 13. It will be understood that such a steering column may be such as is used not only in motor cars, but in connection with

motor boat rudder controls and any apparatus having a revolving shaft encased in a tubular shell. The rectangular section of the housing 10 is composed of flat metal sides and ends and the top face thereof is provided with a well shaped depression 14 descending axially into the housing, as shown in Figure 2. The inner wall of the well 14 is provided with a bearing 15 which supports the outer end of an extensible tumbler shaft 16, the opposite end being loosely mounted about an axially projecting fixed pin 17. The outer end of the shaft 16 projects into the well 14 to receive a dial 18 and knob 19. The diameter of the dial 18 is substantially the same as that of the well 14, so as to permit axial movement as well as rotary movement of the dial throughout the length of the well. Disposed about the edge of the well and mounted on the face of the housing is a circular plate 20 provided with graduations 21 disposed radially thereof.

40 The extensible tumbler shaft 16 is loosely embraced adjacent its rear end by a series of immovable guide discs, in the present instance three such discs are shown, and indicated 22, 23 and 24. These discs are connected together and to a fixed part of the apparatus by web pieces 25, shown in Fig. 5. The discs are all similarly constructed and comprise a circular plate provided with a continuous peripheral channel or guide-way 26, which supports a tumbler ring or selector 27 therein, the latter being split so as to be capable of being expanded to slip over the flanges of the discs. The outer periphery of the ring or selector 27 is provided with evenly spaced radially disposed tapped openings 28 which correspond numerically with the graduations on the face of the ring 20. These threaded openings are adapted to receive the threaded stem of a selector tooth 29 which may be inserted at any position about the periphery of the ring. For each ring 27 there is one tooth 29 which is engaged and adapted to revolve the ring to a predetermined position. The ring selector 27 is further provided with a cut out portion which forms a space 30 and centrally disposed tooth 31. The space 30, as shown in Fig. 3, projects from the periphery of the guide disc radially through the ring selector to the periphery thereof to

establish an open slot. Each guide disc 22, 23 and 24, is provided with a laterally disposed slot 32, see Figures 3 and 4, the slot in each disc being of a height equal to the 5 diameter of the shaft 16 and projecting towards the right while the continuation 32' of the slot 32 at the opposite or left side of the shaft 16 is very much smaller in width and only projects to a point short of the 10 outer periphery thereof. These slots are arranged to facilitate the axial and rotary movement of the shaft 16 through the discs as hereinafter more fully described.

The innermost disc 24 is disposed on a 15 plane substantially one-half the distance between the bottom wall of the housing and the inner face of the well 14, and just in advance of this disc 24 is mounted one end of an L-shaped arm 33, shown in Fig. 2, 20 the other arm 34 being parallel to the axis of the shaft 16 and movable through a circular path closely embracing the peripheries of the ring selectors 27 and intercepted by the projecting selector teeth 29. It will 25 clearly be understood that by revolving the arm 34 about the ring selectors 27 there will be a corresponding rotary movement imparted to the rings until the arm itself has moved in an axial direction to a point where 30 the end of the arm will escape contact with the selector tooth 29. At this point in the operation of each ring selector 27 the tooth 31 and space 30 are brought to rest so that their axes are disposed on a horizontal 35 plane, i. e., on a plane parallel with the bottom and top walls of the housing.

Axially aligned with these teeth 31, when they are moved to the above position, as 40 illustrated in Fig. 2, is a series of openings 35 disposed in a bolt bar 36, the latter being provided with a bolt 37 projecting towards and through the collar 11. The bolt 37 is 45 slidably mounted in a sleeve 38 which is integral at one end with the side of the housing 10 and the opposite end thereof projects through the shell 12 to the face of the steering post 13. Disposed on a plane coinciding with the axis of the bolt 37 is a 50 bolt receiving opening 39 cut radially into the face of the steering post 13, so that as the latter is rotated to a certain position the bolt 37 may be projected into the opening 39 to lock the position of the post with relation to the sleeve or shell 12. As shown 55 in Figure 2, there is a space provided between the peripheries of the rings 27 and the inner face of the bolt bar 36, so as to permit the passage of the arm 34 therebetween.

60 The bolt 37 is operated by means of an L-shaped arm 40 connected at one end to the end of the bolt bar 36, the arm projecting on a line with the bar and then at right angles to lie closely adjacent the inner 65 face of the well 14. A mid-portion of the

arm is cut away to straddle the shaft 16 and the cut portions are bent rearwardly at right angles to form a yoke 41. When the shaft 16 has been moved outwardly or upwardly to complete the combination, as hereinafter 70 described, the radial portion of the arm 33 is inserted between arms of the yoke 41 and by a partial turn of the arm towards the right the arm 40 will be moved in the same direction to retract the bolt 37, while a 75 slight turn in the reverse direction will cause the bolt 37 to move into the opening 39 in the shaft.

The arrangement for moving the shaft 16 axially from one step to the next and to 80 permit rotary movement thereof, comprises a radially disposed pin 42 carried by the shaft 16 closely adjacent its inner end, see Fig. 5. The pin 42 is capable of being moved axially through either group of slots 85 32 and 32' and also in a circular path between the discs 22, 23 and 24. In order to cause the pin 42 to be raised, i. e., axially with the shaft 16, from one step to the next, to first revolve a ring selector 27 into proper position and then move the end of the arm 34 out of the path of the selector tooth 29, a spring comb holder 43 is mounted in a corner of the housing 10 in a position to support a comb spring 44, the latter comprising a series of prongs one member of each projecting between the discs 22, 23 and 24, as shown in Figures 2 and 5. The inner ends of the prongs are provided with inclined portion 45 which project through the 90 slot 32 in the disc to contact with the inclined portion of the next prong. These inclined portions 45 when assembled, as illustrated in Figure 5, form a substantial S shaped structure, with yieldable passages 95 opening into the plane between the discs. The inner end of the innermost spring is adapted to yieldably rest against a rigid plate 46 which is connected at one end to the web projecting from disc 22 and at the 100 other end it is mounted in the comb holder 43. It will be readily understood that with the pin 42 movable through the slots 32, that rotation of the pin 42 towards the right will merely cause it to revolve through the same plane, because in its movement it will engage against the back of the inclined portion 45 of the adjacent spring which in turn will yield and permit the pin to pass. Rotation of the pin in the opposite direction will bring it in engagement with the inclined face of the spring and the pin and shaft 16 will be lifted axially of the axis and into the space between the next discs. The 110 rotation to be effective at the next step will have to be directed in the opposite direction, otherwise the pin 42 will simply move in the same plane between the contacting edges of the springs. The pin 42 and shaft 115 16 may be quickly returned to their initial 120 125 130

positions by merely bringing the pin itself into register with the row of slots 32' and then pushing the dial knob, pin and shaft 16 inwardly.

- 6 To insure a perfect position of the bolt 37 in its two extreme positions I have provided the under surface of the arm 40 with two depressions 47, spaced apart a distance equal to the throw of the bolt, the depressions 47 being adapted to receive a spring pressed ball 48 therein, as shown clearly in Fig. 3.

As will be understood, the characters on the dial ring 20 will correspond to all the possible positions in which the selector teeth 29 may be located and the desired combination will be composed of just the numbers corresponding to the relative positions of the teeth 29 on their respective rings 27; 20 for example, if ring selector 22 carries a tooth 29 at the 10 position, the marker or arrow 49 on the dial 18 must be rotated until it, the marker 49, is registering with the 10 position on the dial ring 20, the respective tooth 31 of the ring 22 will then have been brought into register with the opening 35 in the bolt bar 36. Each ring is manipulated in a similar manner until all of the teeth 31 are in position before the openings 35. However, after any of the rings 22, 23 and 24, are rotated the shaft if rotated farther either in the same direction or in the reverse will ride outwardly as the pin 42 engages the inclined surfaces 35 of the springs 44.

The operation of the mechanism for releasing the bolt 37 is substantially as follows: The dial knob will be in the position shown in Fig. 2, the knob is revolved to bring the marker at a desired character and then turned in the reverse direction until the pin 42 has descended the adjacent spring 44. The knob is then revolved in the same direction until the marker points to the second character of the combination, whereupon the knob is reversed and the shaft and pin 42 moves axially as it rides up on the second inclined spring surface 45. This operation is repeated until the combination is completed and the teeth 31 are all in register with the openings 35. At this stage the yoke 41 will have received the arm 33 and by rotating the shaft 16 slightly towards the right the bolt may be redrawn and the parts free to operate. To return the knob and reset the combination the pin 42, as previously explained is returned to its initial position through the slot 32' in the discs.

Having described my invention what I claim is:

1. A permutation lock of the character described, including a shaft capable of simultaneous rotary and axial movement, to release a bolt, a series of revolving selector members, disposed about said shaft, means

carried by said shaft for rotating said members, and means for moving the shaft axially with each rotation thereof in one direction to disengage the first means from the selector member.

70

2. A permutation lock, as claimed in claim 1 including a housing enclosing the mechanism and having a well to receive the end of said shaft, an indicating dial carried by said shaft and extensible in said well, and a ring mounted on said housing and surrounding the well, the ring being provided with graduations disposed thereabout, whereby the said dial may be rotated to register with the said graduations, substantially as described.

75

3. A permutation lock as claimed in claim 1, including an indicating dial rotatable and extensible with the said shaft, a fixed circular plate surrounding said dial and having radial graduations thereon, corresponding characters disposed on said graduations and about the said selector members, the latter being provided with radial openings in the peripheries thereof, said openings being disposed so as to coincide with the said characters on the members and an insertable tooth for the openings of each member, the said tooth cooperating with the means for rotating the dial, substantially as described.

80

4. A permutation lock, as claimed in claim 1, in which the means for rotating the selector members includes an L-shaped arm engaged at one end in said shaft and the other end of which projects over the edges of the members, the latter being provided with adjustable teeth disposed about their peripheries to be engaged by the overlying portion of said arm, during rotary movement thereof, substantially as described.

95

5. A permutation lock, as claimed in claim 1, in which the means for rotating the selector members includes an L-shaped arm one member of which is engaged in the said shaft while the other member projects over the edges of the selector members, the latter being provided with adjustable projections disposed in the path of said overlying member of the arm, each selector member being provided with slot having a tooth projecting to the periphery of the member and separated therefrom at the sides by a space, and a perforated bolt bar extensible over said teeth and having the said bolt projecting therefrom, a substantially as described.

100

6. A permutation lock, as claimed in claim 1, including a stationary disc disposed between the said shaft and the selector members and provided with peripheral grooves in which the said members revolve, a tooth for each member projecting through a space cut in the member, and a bolt bar extensible over said teeth and into the said space in the members, the said means for rotating the members being adapted to cooperate

115

110

120

125

130

with the said bolt bar to move the latter and the bolt axially, substantially as described.

7. A permutation lock, as claimed in claim 1, in which the said shaft rotates and moves axially about a fixed pin and a housing supporting the said pin at one end and provided with a well at the opposite end to receive indicating dial mounted on the shaft, substantially described.

8. A permutation lock as claimed in claim 1, in which the said means for rotating the selector members includes an arm movable with said shaft and adapted to revolve the said members a predetermined degree and thereafter being moved out of engagement by said means for moving the said shaft axially thereof, substantially as described.

9. A permutation lock, as claimed in claim 1, including a series of separated stationary discs for rotatably supporting the said selector members, the said discs being provided with slots projecting laterally from the said shaft, a pin carried by said shaft and movable therewith through said slots, the means for moving the shaft axially being disposed in said slots and comprising inclined spring members disposed to receive the said pin when rotated in one direction to elevate it and the shaft, substantially as described.

10. A permutation lock, as claimed in claim 1, in which the means for moving the shaft axially comprises a series of spring members having inclined portions which contact with each other closely adjacent the shaft, and a pin carried by the shaft and movable therewith through a path obstructed by the inclined portions of the springs, whereby rotary movement of the pin in one direction will cause it to ride up on the adjacent spring and movement in the opposite direction will permit it to remain on the same plane and slide between the yieldable contacting edges of the said inclined portions of the springs, substantially as described.

11. A permutation lock, as claimed in claim 1, in which the means for moving the shaft axially includes a series of superposed yieldable inclined surfaces, a series of discs having slotted openings through which the said surfaces are disposed, a pin carried by

the shaft and movable in a path obstructed by the surfaces, whereby rotary movement of the pin in one direction causes the latter to ride up on the surfaces to a higher plane and in the opposite direction to remain on the same plane, and a rigid member at one end to receive the pin as the latter is returned to its initial position, substantially as described.

12. A permutation lock, as claimed in claim 1, including a series of grooved discs to support the selector members, a series of web projections connecting the said discs together and to a fixed portion of the said lock, the said discs being provided with radial slots disposed on opposite sides of the shaft, the means for moving the shaft axially being disposed in the slots on one side of the shaft, a pin carried by the shaft and adapted to engage the said means to project the shaft, the slots on the opposite side of the shaft being adapted to permit the pin to be returned to its initial position by only axial movement therethrough.

13. A permutation lock, as claimed in claim 1, in which each selector member is provided with a radial slot having a tooth disposed centrally therein, a bolt bar having perforations axially aligned with said teeth when the latter are moved to the same plane, and an arm carried by the bolt bar and having a yoke the members of which are adapted to be engaged by the means for rotating the selector members and moved through the bolt bar into and out of engagement with the said teeth, substantially as described.

14. A permutation lock, as claimed in claim 1, including a bolt bar operated by the means for rotating the selector members subsequent to the said shaft having been moved axially to its extreme outer position, and a spring actuated engaging means comprising a movable ball for engaging depressions in a portion of the bar, the depressions being spaced apart a distance equal to the movement of the said bar, substantially as described.

In testimony whereof, I, JAMES MAURICE ZWEIMAN, have signed my name to this specification this 15th day of December, 1922.

JAMES MAURICE ZWEIMAN.
